UNITED STATES PATENT OFFICE.

CHARLES L. REIZENSTEIN, OF PITTSBURGH, PENNSYLVANIA.

DESIGN FOR A GLASS PLATE OR OTHER SIMILAR ARTICLE.

52,344.

Specification for Design.

Patented Aug. 27, 1918.

Application filed July 16, 1917. Serial No. 180,948. Term of patent 14 years.

To all whom it may concern:

Be it known that I, CHARLES L. REIZENSTEIN, a citizen of the United States, and residing at 310 South Rebecca St., city of Pittsburgh, county of Allegheny, and State of Pennsylvania, have invented a new, original, and ornamental Design for Glass or other Similar Articles, of which the following is a specification, reference being had to the accompanying drawing, forming part thereof.

Figure 1 is a plan view of a glass plate, showing the new design. Fig. 2 is a frag-

mentary sectional view on the line 2—2, Fig. 1, of part of the plate showing the design. Fig. 3 is a fragmentary sectional view on the line 3—3, Fig. 1 of a part of the plate showing the design.

I claim:

The ornamental design for a glass plate or other similar article, as shown.

CHARLES L. REIZENSTEIN.
